QUICK-ACTING STEAM-GENERATOR.

1,068,368.

Specification of Letters Patent. Patented July 22, 1913.

Application filed May 29, 1913. Serial No. 770,562.

To all whom it may concern:

Be it known that I, WILHELM SCHMIDT, a subject of the King of Prussia, Emperor of Germany, residing at Cassel-Wilhelms-
höhe, Germany, have invented certain new and useful Improvements in Quick-Acting Steam-Generators, of which the following is a specification.

My invention relates to a quick acting generator comprising a system of pipes into one end of which water is fed, while from the other end steam is taken off.

Steam generators of this general type are old and have, as is well known, a very small cubic content, so that in effect only so much water is forced into the generator in a given time as is to be converted into steam in the same time. As a consequence, in generators of this known type, there is no circulation 20 of the water within the pipe system when the generator is first started up or when steam ceases to be drawn from it. Some or all of the individual pipes of the pipe system may therefore, at such time, easily be 25 come dangerously overheated.

The object of the invention herein disclosed is to eliminate the above mentioned disadvantages by providing a surface condenser so connected to the boiler proper 30 that when steam ceases to be taken from the generator it will be condensed and the water flow back into the boiler. This surface condenser I prefer to arrange over the boiler proper.

The character of my invention will be better understood by reference to the drawings which show, diagrammatically, several embodiments thereof, Figure 1 representing a preferred form of the invention, Fig. 2 a 35 similar form provided with a feed water heater, Fig. 3 the arrangement of Fig. 2 with a slightly different arrangement of controlling valves, and Fig. 4 an arrangement similar to Fig. 1 but providing a closing means at the inlet of the condenser instead of a back pressure valve in the outlet of said condenser.

In the drawings the steam boiler proper 40 comprises a coiled pipe *a*, the water being forced into same by suitable pumping means (not shown) at *b* and taken off at *c*. The surface condenser *d* also comprises a coiled pipe arranged in a vessel *e* which is adapted to be supplied with cooling water. The upper end of said condenser is joined by a

pipe *g* to the outlet *c* while the lower end of the condenser is similarly joined by a pipe *h* to the inlet *b*. A feed valve *f* is located in the inlet pipe on the outer side of pipe *h* and the pipe *h* is itself provided with a back pressure valve *i* and a throttle valve *k*, the latter being between the valve *i* and the inlet pipe. A safety valve *m* is provided in the pipe *h* just below the condenser *d*.

The operation of my invention is as follows: When the generator is about to be started up, most of the water will be found in the lower part of the boiler *a*; the pipes *g* and *h* and condenser *d* will be filled with air. As the boiler is heated, steam will be formed which will rise through pipe *g*, will be condensed in the condenser *d*, and will fall through the pipe *h*, the back pressure valve *i* and the throttle *k* into the inlet pipe of the boiler. The air which is contained in the generator should, preferably be driven out in the usual and well-known manner. It is obvious that during this starting up or preliminary heating there will be a continuous circulation of the water and steam in the generator. The throttle valve *k* should be so adjusted during this period that the amount of water capable of passing therethrough in a given time will be less than the amount of water which will be fed into the system when steam is being taken off. When the outlet valve at *c* (not shown) is opened and steam is taken off, the pumping means which supplies water through feed valve *f* should be arranged to start at the same time. As soon as the feed pump starts, the back pressure valve *i*, which is unloaded or only very slightly loaded, will close, since the lower side of the valve is affected by the pressure at which the feed water is forced into the generator, while the upper side of the valve is affected by the much smaller pressure due to the pressure at outlet *c* after it has been diminished by the friction and throttling of the pipes and of the condenser. As soon as the flow from outlet *c* is interrupted the pressure on each side of the valve *i* is equalized and the valve will open so that the water condensing in *d* gradually enters through the back pressure valve *i* and the throttle valve *k* into the lower part of the boiler. In this way the pipes *a* of the boiler are kept constantly in contact with water.

whether the same is flowing or shut off so that there is no danger of said pipes becoming dangerously overheated.

The adjustment of the throttle valve *k* is of particular importance if the generated steam is to be superheated before being used, since, if there is no throttling at all, or insufficient throttling, more water will circulate through the generator in a given time 5 when the boiler is started up than can be evaporated, so that no substantial superheating and sometimes not even a drying of the steam can be obtained. Such an arrangement would obviously be very inefficient as 10 a means of obtaining steam quickly. Similarly, when the steam outflow is cut off, the throttling is of importance, since in such case, if the condenser is emptied too suddenly, water may easily come in contact 15 with the hot walls of the superheater pipes so that there will be an excessive generation of steam and an undesirable high pressure.

Ordinarily, the condenser, when the steam outflow is cut off, is completely filled with 20 water so that the amount of cooling surface which becomes available through the emptying of the condenser is insufficient to condense all the steam which will then be generated, the amount of which steam will even 25 be increased by reason of the larger amount of water which passes from the condenser into the steam generator and is there evaporated. In such cases the pressure of the steam will rise and automatically open the 30 safety valve *m* and a suitable amount of the condensed water will be forced out until 35 equilibrium obtains. When steam is again taken off, the cycle will repeat itself. The safety valve *m* will also operate while steam 40 is being taken from the system, and if the steam pressure becomes too great, as for example, by any sudden decrease of the steam-outflow, the condensed water will be 45 blown off through the safety valve until the pressure sinks to the desired value.

The throttle valve *k* need not be located immediately below the back pressure valve *i*, but may be placed above this valve, or in the inlet pipe of the generator on the inside 50 of pipe *h*. The throttle valve *k* may under some circumstances be entirely dispensed with. In such cases the opening of valve *i* must have a suitable small diameter so as to itself act as a throttle valve. Or, if desired, the valve *i* may be dispensed with instead of the throttle valve, which latter valve must in such case be adjusted so as to completely shut off the pipe *h*. In such case the throttle valve and the steam outlet valve 55 should be so connected with one another that one will be closed when the other is open and vice versa. The safety valve also need not necessarily be located below the condenser as shown in the drawing, but 60 may be placed at any desired point in the

condenser coil. With this last arrangement it would be impossible ever to blow out all the water in the condenser.

The modification shown in Fig. 2 is identical with that shown in Fig. 1 except that a feed water heater *n* is inserted between the inlet *b* and the generator *a*. The mode of operation is similar to that described for the arrangement of Fig. 1.

The modification shown in Fig. 3 is substantially the same as shown in Fig. 2 except that the throttle valve *k* is placed in the pipe *p* connecting the feed water heater and the generator instead of in the pipe *h*. Instead of using an ordinary throttle valve 80 *k* in this embodiment, a special valve arranged to open toward the steam generator *a* and provided with a small permanent bypass may be used. The valve may be ordinarily kept closed by means of a spring 85 which is so adjusted that it will yield to the pressure of the feed pump, but not to the pressure of the overlying water column including the feed water heater. The mode of operation of this modification is similar 90 to that set forth in the form shown in Fig. 1.

In the modification shown in Fig. 4 a shut-off valve *q* is located above the condenser, and in the pipe *h* is the usual throttle valve *k*. Said shut-off valve is preferably connected with the steam outlet valve so that when one is closed the other is open and vice versa. In some cases I find it sufficient to provide, instead of said closing means *q*, a simple back pressure valve 95 adapted to be closed through the pressure of the rising feed water. When a shut-off valve is provided above the condenser, as in this case, it is obvious that the safety valve *m* is non-operative when steam is being taken off. Aside from this the mode of operation of this modification is identical 100 with that set forth in the previous arrangements described.

The vessel *e* which contains the cooling 110 water may be provided with an automatic arrangement, as for example, a float, for regulating the supply of said cooling water so as to maintain a suitable level in the vessel irrespective of the amount of water 115 evaporated therefrom.

The several arrangements described may be used as superheaters instead of as steam generators without any change of structure. In such cases, wet steam instead of water 120 is introduced into the pipe system. Superheated steam may be drawn off when the outlet valve is open, and when the steam outflow is interrupted the arrangement will work as a closed circuit steam generator.

Where in the claims I refer to the surface condenser as being located above the boiler, I mean located at a higher level than the boiler, but not necessarily physically and literally directly above said boiler.

Where in the specification and claims, I refer to the boiler and to the surface condenser as comprising a "coiled pipe," I do not mean to limit these elements to pipes coiled in the manner shown by the illustrations. What I mean by the expression "coiled pipe" is any continuous length of pipe either coiled screw-like as in the drawings, or arranged in a flat coil or arranged 10 with lengths laid side by side, sometimes spoken of as a "serpentine" arrangement; other equivalent arrangements will readily suggest themselves, are known in the art, and are claimed by me as within the scope 15 of the words just referred to.

Other changes may be made within the spirit of my invention which is defined by the following claims:

I claim:

20 1. In a steam generator, the combination of a boiler comprising a coiled pipe having an inlet for water and an outlet for steam, and a surface condenser above said boiler and directly connected thereto so that steam 25 flows to said condenser and thence returns as water to the boiler.

2. In a steam generator, the combination of a boiler comprising a coiled pipe having an inlet for water and an outlet for steam, 30 and a surface condenser also comprising a coiled pipe one end of said condenser pipe being connected near said outlet and the other end being arranged to discharge into the boiler nearer its inlet end.

35 3. In a steam generator, the combination of a boiler comprising a coiled pipe having an inlet for water and an outlet for steam, and a surface condenser also comprising a coiled pipe located above said boiler the upper 40 end of said pipe being joined near said outlet and the lower end being arranged to discharge into the boiler nearer its inlet end.

4. In a steam generator, the combination of a boiler comprising a coiled pipe having an inlet for water and an outlet for steam, a surface condenser also comprising a coiled pipe located above said boiler the upper end 45 of said pipe being joined near said outlet and the lower end being arranged to discharge into the boiler nearer its inlet end, and means for preventing the flow of feed water through the condenser into the boiler.

5. In a steam generator, the combination of a boiler comprising a coiled pipe having 55 an inlet for water and an outlet for steam, a surface condenser also comprising a coiled pipe located above said boiler the upper end of said pipe being joined near said outlet and the lower end being arranged to discharge 60 into the boiler nearer its inlet end, and closing means in the pipe between the condenser and said lower end so that feed

water may not pass through the condenser into the boiler.

6. In a steam generator, the combination 65 of a boiler comprising a coiled pipe having an inlet for water and an outlet for steam, a surface condenser also comprising a coiled pipe located above said boiler the upper end of said pipe being joined to said outlet and the lower end being arranged to discharge into the boiler nearer its inlet end, means for preventing the flow of feed water through the condenser into the boiler, and a throttle valve for causing the condensed water to 70 flow slowly back to the boiler.

7. In a steam generator, the combination 75 of a boiler comprising a coiled pipe having an inlet for water and an outlet for steam, a surface condenser also comprising a coiled 80 pipe located above said boiler the upper end of said pipe being joined to said outlet and the lower end being arranged to discharge into the boiler nearer its inlet end, means for preventing the flow of feed water through the condenser into the boiler, a throttle valve for causing the condensed water to 85 flow slowly back to the boiler, and a safety valve between the upper end of the condenser and the inlet.

8. In a steam generator, the combination 90 of a boiler comprising a coiled pipe having an outlet end for steam, a feed water heater at the other end of said pipe, a surface condenser also comprising a coiled pipe located 95 above said boiler the upper end of said condenser being joined to said outlet and the lower end to the inlet side of the feed water heater, and means between the upper end of said condenser and the feed water heater for 100 preventing water from passing through the condenser to the boiler.

9. In a steam generator, the combination 105 of a boiler comprising a coiled pipe provided with an inlet for water and an outlet for steam and a surface condenser directly connected to said boiler between inlet and outlet so that steam flows to said condenser and returns as water to the boiler.

10. In a steam generator, the combination 110 of a boiler comprising a coiled pipe provided with an inlet for water and an outlet for steam and a surface condenser having separate pipe connections for steam and water the steam connection opening from 115 the boiler between its inlet and outlet.

In testimony whereof, I have hereunto set my hand in the presence of two subscribing witnesses.
